MAGNETIC CORE DRIVER AND INHIBIT CIRCUIT
James J. Nyberg, Woodland Hills, Calif., assignor to the
United States of America as represented by the Secretary
of the Air Force

Filed June 25, 1963, Ser. No. 290,572
2 Claims. (Cl. 307—88)

This invention relates to intelligence recording, and particularly to the recording of "and," "or," and related signals by use of "logic" circuitry.

In logic circuitry the presence or absence of an electrical pulse, in any given pulse transmitting period, denotes whether a condition to be monitored has occurred or has not occurred, according to the code pattern pre-assigned to the circuitry.

In digital computers supplied with coded signals previously stored in magnetic memory cores, it is important to have a reliable method of inhibiting the unintentional storage of "1" signals during writing cycles marked by false logic input to the "flip-flop" two-state devices controlling the signal storage operations. The present invention provides such a method, and novel means for practicing it.

In the drawing, a pair of NPN transistors Q_1 and Q_2 combine with a pair of PNP transistors Q_3 and Q_4 , and associated diodes CR1 to CR16, inclusive, and resistors R1 to R10, inclusive, to provide two parallel gating circuits operable alternately in response to the application of an "or" signal pulse to input N or input pin J, as the case may be, while an "AND" signal pulse applied to input pin L, or pin K, is buffered by diode CR2, or CR10.

"Trimpot" potentiometers R5 and R10 are adjustable to adjust the output currents of the two circuits to 220 milliamperes, at the points A and H, respectively, leading to the memory core planes of the signal storage unit, not shown. Input leads 10 and 11 join at junction point D, leading to transistor Q_1 and leads 12 and 13 join at junction point E, leading to transistor Q_2 . Emitter leads from Q_1 and Q_2 carry the same negative voltage (-4 volts) as is applied to the novel error eliminating protective circuit, now to be described.

An error inhibiting circuit, including an additional transistor Q_5 , is interposed between a clock pulse generator 20 and the input junction points D and E, by way

2

of buffer diodes CR3 and CR4, respectively, in the branches 21, 22, on the emitter follower output side of transistor Q_5 . As noted above, the clock pulses supplied to the base of transistor Q_5 are of -4 volts in magnitude, which is not enough to prevent activation of the selected memory core connecting with output A, or H, as the case may be, in any pulse cycle marked by a true logical input at either gate N or gate J. However, on the occurrence of a false input at either N or J, the emitter follower leads 21 and 22 will both carry sufficient additional voltage to activate both memory cores fed by terminals A and H (by way of Q_1 - Q_2 - Q_3 - and Q_4) to enter a "zero" signal therein, and thereby prevent the entry of a "1" signal into either one of the cores. This additional voltage will be supplied by way of booster lead 25 tapping into the base circuit of transistor Q_5 and delivering thereto the additional voltage supplied by way of AND lead 12 (or 10) both of which tap into lead 25 at junction point 26.

What I claim is:

1. In a signal storage system, a pair of parallel circuits coupled to magnetic cores, said circuit to receive, selectively, a "1" or "0" signal pulse, means for sending such a signal pulse to a selected one of said parallel circuits, and means for sending an inhibit pulse to both said parallel circuits, simultaneously, in response to false operation of said first-named sending means, wherein said inhibit pulse sending means includes a clock pulse-driven transistor having an emitter follower output, and branching circuits connecting said emitter follower output to said parallel circuits.

2. In the signal storage system of claim 1, means including AND circuits interposed between said signal sending means and said transistor to control the voltage response of said transistor in accordance with the truth or falsity of the logic input to said signal sending means.
